Apparatus for consolidating plastic materials by means of internally applied vibrations, including a carriage having a supporting frame, a plurality of vibrators loosely depending therefrom, and a second member attached to the carriage and above or behind or partly above and partly behind the vibrators, the second member being screed-like in form and arranged to travel across the material at a selected distance above the grade for striking off the plastic material to a predetermined elevation and simultaneously vibrating the material.

Another object is to provide suitable apparatus including vibrating mechanisms adapted to be inserted into and drawn through the mass of plastic material so as to subject the same at suitable intervals to vibrations and thus result in properly consolidating the entire mass.

Among the further objects of my present invention is to provide a means for agitating the entire mass to its full depth over a relatively short period of time, thus providing less oppor-

tunity for impurities such as laitance to rise to the surface.

With these and other objects in view my invention consists in the steps hereinafter designated and my apparatus consists in the construction, arrangement and combination of the various parts thereof, whereby the objects contemplated are attained, as set forth more in detail in my specification, pointed out in my claims and illustrated in the accompanying drawing, in which:

Figure 1 is a front elevation of a carriage for my apparatus for consolidating materials by internally and surface applied vibrations, together with one of the forms of vibrating apparatus.

Figure 2 is a sectional view on the line 2-2 of Figure 1 showing the parts on an enlarged scale.

Figure 3 is an enlarged sectional view of one of the individual vibrators.

Figure 4 is a sectional view of another form of vibrating apparatus adapted for use on a carriage similar to that shown in Figure 1 taken on the line 4-4 of Figure 5.

Figure 5 is a side elevation of a carriage incorporating the form of device shown in Figure 4.

This application is a continuation in part of my application 725,580 filed May 14, 1934, and my application 228,625 filed September 6, 1938, which matured into Patent No. 2,255,344 on September 9, 1941.

In making concrete pavements and concrete foundations for other wearing surfaces, the concrete is ordinarily placed upon the subgrade to such a depth that when struck off by a screed or planer, it will have the desired elevation and contour. Various methods have been used to consolidate the concrete. Frequently a screed or planer with a substantially vertical front face is drawn over the concrete. Usually the screed rests upon the side forms.

The screed imparts to the concrete at the surface a slight kneading or working action which quite often produces a surface of pleasing appearance, but which does not beneficially affect the major portion of the concrete below its surface.

Due, moreover, to the inertia or dead weight of the concrete, the force of any tamping blows is absorbed by the upper portion of the concrete, with the result that the lower portion of the mass is not beneficially affected.

Other methods more efficacious than the two above described consist in vibrating the screed, or in passing over the surface a vibrating roller.

Some methods agitate the concrete mass to its

UNITED STATES PATENT OFFICE

Apparatus for consolidating plastic materials by means of internally applied vibrations, including a carriage having a supporting frame, a plurality of vibrators loosely depending therefrom, and a second member attached to the carriage and above or behind or partly above and partly behind the vibrators, the second member being screed-like in form and arranged to travel across the material at a selected distance above the grade for striking off the plastic material to a predetermined elevation and simultaneously vibrating the material.

Application July 7, 1941, Serial No. 401,330

(Cl. 94—48) *carriage, vibrators, and screed*

3 Claims.

My invention relates to vibrating machines and particularly machines for compacting concrete and leveling off the surface of the mass so that it is brought to a proper grade.

One of the objects of my invention is to provide a new and improved, durable and inexpensive apparatus for consolidating plastic materials by internally applied vibrations.

Another object is to provide an apparatus for consolidating plastic materials by subjecting spaced points thereof to internally applied vibrations by means of a supporting member having a plurality of vibrators loosely depending therefrom so that they will easily slip over and around obstructions such as reinforcing bars, the supporting member being movable to successive positions for subjecting the entire mass of a pavement or the like to the vibrations inasmuch as the concrete while still plastic and before initial set has occurred will be vibrated at considerable distance from the points at which the vibrating elements are inserted.

Another object is to provide a new and improved apparatus including a supporting frame or carriage arranged to be propelled by power or by manual means along a concrete slab, which incorporates one or more vibrators arranged to be propelled through the roadway material by the frame, the vibrators being operated by a revolving out-of-balance weight associated with each vibrator, and the axis of the out-of-balance weight being either inclined from the horizontal or approximately horizontal. It is contemplated that the vibrator or vibrators may be partially or wholly submerged in the roadway material.

Also among the objects is to provide, where occasion requires it, a second member attached to the carriage and above or behind or partly above and partly behind the previously described vibrators, this second member being screed-like in form and arranged to travel across the material at a selected distance above the grade for striking off the plastic material to a predetermined elevation and simultaneously vibrating the material.

Another object is to provide suitable apparatus including vibrating mechanisms adapted to be inserted into and drawn through the mass of plastic material so as to subject the same at suitable intervals to vibrations and thus result in properly consolidating the entire mass.

Among the further objects of my present invention is to provide a means for agitating the entire mass to its full depth over a relatively short period of time, thus providing less oppor-

full depth, but due to the fact that in some cases the vibratory energy is applied to the concrete mass at its upper surface, ill effects have been observed.

When the vibratory energy is applied to the surface of the concrete mass, the major portion of the agitation occurs in the upper part of the mass, and when enough energy is applied to produce sufficient agitation in the lower portion, the excess energy applied to the upper portion tends to bring to the surface various impurities, such as inert and non-cementitious materials, producing a condition called laitance. This produces a surface skin which is weak and tends to scale off, leaving the concrete surface rough and imperfect.

I have found that by applying the vibratory energy to the interior of the mass of material, at closely spaced locations and to the full depth of the mass the concrete thereby receives uniform vibrating treatment through its full depth, eliminating all voids, expelling entrapped air and surplus water, and giving to the mass of concrete the maximum degree of density and resistance to the infiltration of moisture without causing the undesired impurities to rise to its surface.

With my present apparatus, I can apply vibration within the mass of concrete by inserting, at closely spaced intervals and to the full depth of the mass, one or more vibratory units.

I may also simultaneously vibrate the concrete by the application of surface vibrations from a vibrating screed-like member, and this member may also be utilized to strike off and level the concrete.

In Figure 1, I show a frame 10. It is a box-like carriage construction and my subsequent description of Figures 2 and 3 apply to it and to vibrating elements 12 depending therefrom. The frame 10 is provided with supporting runners or wheels or the like 14 adapted to travel on side forms 16 of a subgrade 18. Suitable hold down rods 22 are associated with the side forms to retain them in position in the ordinary manner. Concrete or other plastic material 20 is illustrated between the side forms. The concrete deposited between the side forms is initially roughly leveled off. The frame spans the concrete between the side forms 16.

The frame may be provided with manipulating handles 24, preferably attached to the frame by rubber bands or the like 26 associated with pins 28 of the supporting member and handles 24. This method of attachment prevents transmission of vibrations from the frame 10 to the handles 24 and is shown more in detail in my Patent No. 2,018,294 issued October 22, 1935.

The frame 10 and its vibrating elements 12 can be raised and lowered, moved longitudinally of the roadway, or be otherwise manipulated by the handles 24.

The vibrating elements 12 are so carried by the frame that they may penetrate into the plastic mass 20 to any desired depth, preferably the full depth of the plastic mass as indicated.

As a means of universal mounting, I have shown a ring 30 for each vibrating element 12 pivoted on a horizontal axis by means of pintles 32 mounted in brackets 34 secured to the bottom 10a of the box-like supporting element 10. The ring 30 in turn supports pintles 36 of the vibrating element 12 which are arranged on an axis at right angles to the axis of the pintles 32.

By the universal mounting just described, it will be obvious that the vibrating elements 12

will normally depend downwardly into the concrete mass 20, but can be deflected sidewise away from a center joint or the like shown at 40 in Figure 1, or may be deflected rearwardly during travel of the carriage, or to pass over rocks 42 or other obstructions as shown at the left side of Figure 1. In Figure 2 it is apparent how they may be rotated upwardly about the axis of the pintles 32 to slide over the tops of lateral reinforcing bars 44.

In combination with the vibrating elements, a finishing screed or planer 46 may be provided either connected as by a bracket 48 with the frame 10 or independent of the vibrating element support. Thus after the concrete is compacted by the vibrating elements, it is leveled off to the desired contour by the finishing screed 46.

In Figure 4, I have shown another form of the invention including a frame 50, the front portion of which forms a strike-off screen and vibrating elements 12' supported thereon by flexible connecting tubes 52 extending from elbows 54. The elbows 54 project into the plastic material 20, permitting the vibrating elements 12' to trail behind them and assume positions substantially imbedded in the plastic material and adjacent the subgrade. Due to the flexible tubes the vibrators 12' can shift about in their forward course so as to slide over and around obstacles such as stones and reinforcing bars.

In connection with either form of the invention, a finishing screed 60 may be provided having a vibrator motor 62 and a vibrator weight 64 for vibrating it and thereby subjecting the surface of the concrete to vibrations as it is finished off by the plate 66.

Where desired an initial strike-off screed 66 may be used to rough-level the surface prior to passing the finishing screed over it. Where the strike-off screed is used with the vibrators 12 mounted as shown in Figures 1 and 2, the strike-off screed may be also vibrated to some extent. Moreover, when the strike-off screed 66 is employed it is preferable to use power operation rather than hand operation for the frame 50, or the frame 10, whichever may be the one being used.

When the vibrating elements 12 or 12' as the case may be are operated within the plastic material 20, the energy from each element affects the plastic mass to a considerable distance in every direction. The elements are sufficiently close together so that the area each affects overlaps the areas affected by the adjacent elements, thus providing adequate vibration for the entire mass of the plastic material 20.

When the apparatus is positioned as shown in Figure 1, it will vibrate the plastic mass over a zone of considerable width measured laterally from the longitudinal axis of the frame 10. In operation, when the plastic mass 20 has been sufficiently vibrated at one location, the apparatus may be dragged or lifted to a new position longitudinally of the roadway or otherwise, and there allowed to operate for a suitable interval, and by successive movements of this kind, the entire area of the plastic mass may be consolidated and compacted.

In many pavement and foundation structures where fixed objects occur, such as the center joints 40, large rocks 42, or reinforcing rods 44, the path of the vibrators must be shiftable. If the elements 12 were rigidly attached to the frame 10, such objects might be displaced from their desired positions or the vibrating appara-

tus might be damaged or caused to operate inefficiently. Therefore the vibrating elements are flexibly attached to the supporting member so that when objects are encountered, the vibrating elements may be easily deflected from their normal positions.

The type of apparatus shown in Figure 4 is especially designed for operation by continuously moving the frame 50 along the roadway with the vibrating elements remaining continually in the concrete. The elements may be dragged along while partially inserted in the concrete.

Ordinarily a planer or finishing screed like that shown in Figure 2 which is not provided with a vibrator operates sufficiently to bring the surface of the concrete to the desired contour. When the concrete has an extremely non-flowing characteristic, however, a vibrating finishing screed may be used, preceded if desired by a strike-off screed. The vibrating finishing screed additionally agitates the concrete and causes all voids remaining after the vibrator elements have passed through, to be filled up.

Flexible tubing, springs, rubber rings and the like may be provided for supporting the vibrating elements 12, the types of supports I show being only by way of illustration. With respect to the vibrating mechanisms for the elements 12, they can be contained in the elements as disclosed, or the frame 10 can be vibrated for the purpose of vibrating all the elements 12 and without the necessity of providing each one with a vibrating mechanism.

Some variations may be followed in the practice of my invention without departing from the real spirit and purpose of my invention. Accordingly, it is my intention to cover by my claims such equivalent structure as may be reasonably included within their scope.

I claim as my invention:

1. In an apparatus for treating material which becomes plastic when vibrated, the combination of a carriage movable over the material, supporting elements at the ends of the carriage, an elongated vibrating element, flexible means for connecting said element to the carriage for extending at least partially beneath the surface of the material, and a finishing screed secured to the carriage in position rearward of the leading end of said vibrating element, said

finishing screed being located substantially at the level desired for the finished surface of said material, a vibrating member mounted on the finishing screed for vibrating said last screed, and means on the carriage for actuating said vibrating element whereby the material being treated can be internally vibrated and surface vibrated during the travel of the apparatus.

2. In an apparatus for treating material which becomes plastic when vibrated, the combination of a carriage movable over the material, supporting elements at the ends of the carriage, an elongated vibration imparting element connected to the carriage for extending at least partially beneath the surface of the material, vibration creating means within the element and a finishing screed secured to the carriage in position rearward of the leading end of said vibrating element, said finishing screed being located substantially at the level desired for the finished surface of said material, a vibrating member mounted on the finishing screed for vibrating said last screed, and means on the carriage for actuating said vibrating element whereby the material being treated can be internally vibrated and surface vibrated during the travel of the apparatus.

3. In an apparatus for treating material retained within the sides of a form and which becomes plastic when vibrated, the combination of an elongated carriage movable laterally with respect to its long dimension extending from side to side of said form, supporting elements at the ends of the carriage adapted to support the carriage on the form during movement therealong, a plurality of laterally spaced elongated vibrating elements connected to the carriage disposed transverse to the long dimension of the carriage extending at least partially beneath the surface of the material and substantially parallel to the direction of movement of the carriage, and a finishing screed secured to the carriage parallel to the long dimension thereof and in position rearward of the leading end of said vibrating elements, said finishing screed being located substantially at the level desired for the finished surface of said material, a vibrating member mounted on the finishing screed for vibrating said last screed, and means on the carriage for actuating said vibrating elements.

ROBERT WILLIAM BAILY.
